UNITED STATES PATENT OFFICE

ALFRED E. WOOD, OF BRIDGEPORT, CONNECTICUT, ASSIGNOR TO THE SINGER MANUFACTURING COMPANY, OF ELIZABETH, NEW JERSEY, A CORPORATION OF NEW JERSEY

BUTTONHOLE-CUTTING MECHANISM

Application filed December 4, 1931. Serial No. 578,967.

This invention relates to sewing machines of the type used for making buttonholes and has for an object to provide such a machine with a buttonhole-cutting mechanism including a pair of pivoted cutter-levers having a powerful cutting action, enabling the device to cut through heavy material, without restriction of the depth of the throat of the cutter-levers.

10 With the above and other objects in view, as will hereinafter appear, the invention consists in the devices, combinations, and arrangements of parts hereinafter set forth and illustrated in the accompanying drawings of a preferred embodiment of the invention, from which the several features of the invention and the advantages attained thereby will be readily understood by those skilled in the art.

20 Fig. 1 is a vertical sectional view taken longitudinally of the frame of a buttonhole sewing machine, showing the buttonhole-cutting mechanism in side elevation; the cutter-levers being at rest in retracted position.

25 Fig. 2 is a similar view with the cutter-levers advanced to buttonhole-cutting position and partially closed upon the work. Fig. 3 is a view similar to Fig. 2 but with the cutter-levers fully closed upon the work. Fig. 4 is a horizontal section through the bracket-arm standard of the machine, showing the buttonhole-cutting mechanism in plan. Fig. 5 is a reverse side elevation of the rear end-portion of the upper cutter-lever together with its actuating cam. Fig. 6 is a transverse section through the rear end-portion of the upper cutter-lever on the line 6-6, Fig. 5, showing the actuating cam in elevation. Fig. 7 is a disassembled perspective view of the front end-portion of the upper cutter-lever or punch-carrier. Fig. 8 is a similar view of the parts from another angle. Fig. 9 is a disassembled perspective view of the punch and its actuating lever. Fig. 10 is a section taken on the line 10-10, Fig. 1. Fig. 11 is a plan view of the die-element of the buttonhole-cutting mechanism, and Fig. 12 is a sectional view of the die-element.

The sewing machine illustrated is of the buttonhole sewing type and is designed par-

ticularly to cut and sew round ventilating eyelets in heavy materials, such as the side-walls of mattresses, quilts, etc.

For cutting holes in work of this character the simple lever-mechanism heretofore used is subjected to severe strain which is likely to cause distortion or breakage of the parts. While, of course, the power of simple cutter-levers may be increased by shifting the fulcrum of such levers nearer to the cutting elements, such a shift will unduly restrict the depth of the throat of the cutter-levers and will also seriously reduce the vertical separation of the cutting elements necessary for the admission of thick work.

The machine is constructed with a bed 1, from which rises the standard 2 of the bracket-arm 3 terminating in the head 4 carrying the usual reciprocating and rotating needle-mechanism 5 which cooperates with the usual looper-mechanism 6 below the bed 1 in the formation of button hole-overseaming stitches; the mechanism being substantially that disclosed in the Allen Patent No. 1,162,207, of November 30, 1915.

The work is clamped between the lower work-supporting plates 7 and upper clamp-feet 8 which expose a circular area of work for the action of the stitch-forming mechanism. During the sewing operation, the work within this exposed area is supported against the thrust of the needle by the usual needle-throat member or "button" 9 which is pivotally mounted at 10 on the turret 11 carrying the looper-mechanism 6. During the sewing, this needle-throat member is rigidly maintained in the vertical position shown in Fig. 1, but is temporarily tilted laterally out of sewing position to the position shown in Fig. 2, when the cutter-levers are advanced to cut the buttonhole or eyelet, as disclosed in the Allen Patent No. 1,048,786, of December 31, 1912. It is to be understood that the word buttonhole is used herein in its broadest sense, as understood by those skilled in the art, to cover an overseamed hole of any size, shape, or contour, including round eyelets.

In machines of the type in question it is common to provide a buttonhole cutter-shaft 11

- 12 which is stationary during the sewing and makes one complete revolution before or after the stitch-forming mechanism operates. This cutter-shaft carries a cutter-advancing 5 and -retracting cam 13 which is connected by the usual link 14 to the travelling fulcrum-block 15 slidably mounted in suitable ways in the bed 1. The cutter-shaft also carries the cutter-closing cams 16 and 17.
- 10 Fulcrumed on the screw-pin 18 carried by the travelling fulcrum-block 15 are the upper and lower cutter-levers, 19 and 20, respectively, the rear ends of which are cooperatively related with the respective cutter-closing cams 16 and 17.
- 15 The lower cutter-lever 20 has mounted thereon by screws 21' a die 21 which is adapted to be entered by the punch 22 slidably mounted in the hole 23, Figs. 7 and 8, in the head-piece 24 which is secured to the front end of the upper cutter-lever 19 by the bolt 25. The lever 19 is formed with a transverse groove 26 entered by a transverse rib 27 on the head 24, and adjusting screws 28 are provided at opposite sides of the upper cutter-lever 19 to bear upon the sides of the head-piece 24 and enable the punch 22 to be accurately registered with the stitched figure or eyelet. The die 21 is adjustable on the lower cutter-lever 20 to register with the punch 22; the holes for the screws 21' being enlarged for this purpose.
- 20 The punch 22 is formed with a guide-head 22' which fits between the spaced ears 29 of the head-piece 24. Such guide-head 22' is formed with a throat 30 entered by the rounded tongue 31 at the forward end of the auxiliary punch-operating lever 32 fulcrumed at 33 on the upper cutter-lever 19.
- 25 A second auxiliary punch-operating lever 34 is fulcrumed on the upper cutter-lever 19 at 35 in position for its forward end to engage under the rearward end of the auxiliary punch-operating lever 32. A leaf-spring 36 screwed to the upper cutter-lever bears upon the adjustable abutment-screw 37 and yieldingly urges the punch-element 22 upwardly in its carrier-head 24, holding such punch-element in the position shown in Fig. 1, relative to the upper cutter-lever 19.
- 30 Mounted on the rear end of the second auxiliary-lever 34 is a screw 38 which passes through a slot 39 in a link 40 anchored by the screw 41 to the lower cutter-lever 20.
- 35 The cutter-levers are yieldingly held open by the spring 42 which connects them together and also holds such levers in engagement with their respective cams, 16 and 17.
- 40 *Operation*
- When the machine is stationary, the cutter-levers are open and in their retracted position removed from sewing position, as shown in Fig. 1. The screw-pin 38 is intermediate 45 the ends of the slot 39 in the link 40.
- The between-substance or work-piece *w* is introduced into the work-clamp and held as shown in Fig. 1.
- 40 After the machine is started the cutter-shaft 12 is connected to its driving means for one revolution and then brought to rest in the customary manner. During the rotation of the cutter-shaft, the cam 13 first advances the fulcrum-block 15 to carry the punch and die to cutting position. Following this the 75 cam 16 partially closes the upper cutter-lever to the position shown in Fig. 2; the screw-pin 38 travelling idly along the slot 39 in the link 40 and, because of this lost motion, causing no motion of the punch 22 relative to its carrier-lever. The cam 17 has also partially closed the lower lever 20 and slightly elevated the die.
- 45 During the continued movement of the shaft 12, the screw-pin 38 strikes the upper end of the slot 39 in the link 20 and, as the cutter-levers are further closed by the cams 16 and 17, the punch is powerfully and suddenly driven through the work *w* and slightly into the die 21; the lower end of the punch being preferably ground to a blunt chisel-shape, as shown in Fig. 9, to favor its shearing action on the work in cooperation with the die.
- 50 During the further movement of the shaft 12, the cutter-levers are opened and retracted to their initial position, Fig. 1.
- 55 To effect a positive initial opening movement of the upper cutter-lever, to overcome any possible sticking tendency of the punch in the die, the upper cutter-lever may be provided at its rear end with a block 43 having in its side face a cam-slot 44 which is entered by the roller 45, as shown in Figs. 5 and 6, to positively retain the lever 19 in engagement with the cam 16 while the roller 45 is travelling along the cam-slot 44.
- 60 Having thus set forth the nature of the invention, what I claim herein is:—
1. Buttonhole-cutting mechanism for sewing machines having, in combination, a die, a die-carrier, a punch-carrier, a punch mounted on and movable relative to said punch-carrier, means for relatively approaching said die and punch-carrier while said punch is held stationary relative to said punch-carrier, and means for thereafter moving said punch relative to said punch-carrier and into said die, said means including a lever system mounted on the punch-carrier and connected to said die-carrier. 110
2. Buttonhole-cutting mechanism for sewing machines having, in combination, a die, a die-carrier, a punch-carrier, a punch mounted on and movable relative to said punch-carrier, means for relatively approaching said die and punch-carrier while said punch is held stationary relative to said punch-carrier, and means for thereafter moving said punch relative to said punch-carrier 120
3. Buttonhole-cutting mechanism for sewing machines having, in combination, a die, a die-carrier, a punch-carrier, a punch mounted on and movable relative to said punch-carrier, means for relatively approaching said die and punch-carrier while said punch is held stationary relative to said punch-carrier, and means for thereafter moving said punch relative to said punch-carrier 125
4. Buttonhole-cutting mechanism for sewing machines having, in combination, a die, a die-carrier, a punch-carrier, a punch mounted on and movable relative to said punch-carrier, means for relatively approaching said die and punch-carrier while said punch is held stationary relative to said punch-carrier, and means for thereafter moving said punch relative to said punch-carrier 130

and into said die, said means including a lever system mounted on the punch-carrier and having a lost-motion connection with said die-carrier so as to have a sudden action as the punch-carrier and die are completing their relative approach.

3. In buttonhole-cutting mechanism for sewing machines, the combination with a die-carrying member, of a pivotally mounted punch-carrying lever, a punch-member mounted on and movable relative to said lever, an auxiliary punch-operating lever fulcrumed on said punch-carrying lever and connected to said punch, an operative connection between said auxiliary lever and said die-carrying member, and means for rocking said punch-carrying lever on its pivot.

4. In a buttonhole sewing machine, a buttonhole cutter-shaft, upper and lower cutter-levers pivotally connected together, an upper cutting element carried by and movable relative to the upper cutter-lever, cutter-lever-closing means on said cutter-shaft, and means for moving said upper cutting-element relative to said upper cutter-lever, said means including an auxiliary cutter-lever fulcrumed on said upper cutter-lever and connected to said lower cutter-lever.

5. Compound buttonhole-cutting mechanism for sewing machines comprising a travelling fulcrum-block, cutter-levers fulcrumed on said block, a cutting element carried by and movable relative to one of said levers, compound lever-mechanism carried by said levers and connected to move said cutting element relative to its carrier-lever, a cutter-shaft, and cams on said shaft and connections for imparting travelling movements to said fulcrum-block and for closing 40 and opening said cutter-levers.

6. Compound buttonhole-cutting mechanism for sewing machines comprising, relatively movable pivotally connected cutter-levers, a cutting element carried by and movable relative to one of said levers, and compound lever-mechanism, carried by said levers and connected to be actuated by the relative pivotal movement of said levers and to move said cutting element relative to its carrier-lever.

In testimony whereof I have signed my name to this specification.

ALFRED R. WOOD.
